ROTARY KILN

Henry Vanderwerp, Cleveland, Ohio

Application June 30, 1939, Serial No. 282,105

1 Claim. (CL 34—63)

The invention relates to improvements in rotary kilns of the type commonly used for producing cement clinker, the present invention constituting an improvement on the constructions of kilns disclosed in my prior Patents No. 2,132,709, granted me October 11, 1938, for Rotary kiln, and No. 2,132,710, granted me October 11, 1938, for Apparatus for producing cement clinker.

The primary object of the present invention is the provision of an improved means for introducing air into such kilns.

Another object of the invention is the provision of a kiln of the character indicated so constructed and arranged as to occupy less lateral and vertical space.

Other objects will appear hereinafter.

The invention consists in the combinations and arrangements of parts hereinafter described and claimed.

The invention will be best understood by reference to the accompanying drawings forming a part of this specification and in which

Fig. 1 is an end view, with portions broken away, disclosing a rotary kiln embodying the invention;

Fig. 2 a side view of the discharge end of said kiln;

Fig. 3 an enlarged partial section, with portions broken away, taken substantially on line 3—3 of Fig. 2;

Fig. 4 a partial section taken substantially on line 4—4 of Fig. 3;

Fig. 5 a partial section taken substantially on line 5—5 of Fig. 3;

Fig. 6 a section taken substantially on line 6—6 of Fig. 5;

Fig. 7 an end view of the discharge end of a modified form of kiln; and

Fig. 8 a partial side view and section corresponding with Fig. 7.

The embodiment of the invention illustrated in Figs. 1, 2, 3, 4, 5, and 6 comprises a suitable rotary inclined kiln 10 having a recuperator and cooling chamber 11 at its discharge end provided with air ducts or flues 12 in its periphery and tuyère blocks or heads 13 arranged on the inside thereof in open communication therewith. The kiln proper, including the recuperator and cooling chamber, is fully disclosed and described in my said prior patents, and more particularly in Patent No. 2,132,710, and forms no part of the present invention except in so far as the same cooperates with the parts to be presently described.

An annular wind box or air manifold 14 is seated as shown against the discharge end of the kiln and a diaphragm or partition 15 is arranged as shown in the upper and side portions thereof to block or cut off a supplemental air chamber 16 having its lower ends closed by transverse walls 17 and 18 as best shown in Fig. 3. An arcuate air port 19 is formed in the lower portion of the inner wall of the wind box and is of an angular extent sufficient to register with a number of ports 20 formed in an annular blast ring 21 secured as shown over the ends of the air ducts 12 and whereby air from the wind box 14 will be freely admitted to the lower air ducts 12 as the port 19 is passed during the rotations of the kiln. As best shown in Fig. 3, the load of clinker being treated tends to accumulate as shown over the tuyère blocks 13 corresponding with the ports 20 thus open to the admission of air so that in normal operation the air thus admitted will pass upwardly through the load of clinker being treated for the purpose fully explained in my said patents.

To facilitate the rotation thus occurring between the kiln and the wind box, the blast ring 21 is preferably provided with bearing rings 22 and 23 contacting with and rubbing against the inner side wall of the wind box as shown. Suitable barriers in the form of brass angles 24 are also preferably provided between the rings 22 and 23 to prevent the escape of air through the port 19 and the space between the blast ring 21 and the inner wall of the wind box 14 to the upper ports 20 and thereby to escape entry through the load of clinker and enter the upper portion of the kiln. If desired, the arcuate port 19 may be made adjustable in length to vary the quantity of air admitted through the load of clinker and suitable valves may be provided in the partition or diaphragm 15 for admitting air to the upper ports 20 and thence to the upper portion of the kiln as is more fully explained in my said prior patents and for the purposes indicated.

As best shown in Figs. 1 and 2, the wind box 14 is yieldingly mounted on flanged wheels 25 running upon tracks 26 and whereby said wind box may yield to accommodate expansions and contractions of the kiln under the influence of the intense heat to which it is subjected. Cables 27 are connected at opposite sides with the wind box 14 and lead over grooved pulleys 28 to weights 29 whereby the wind box is held yieldingly seated against the end of the kiln as will be readily understood. A flexible connection 30

is provided for supplying air under pressure to the wind box 14 from a source, not shown.

A firing hood 31 is arranged as shown adjacent the wind box 14 and is mounted upon wheels 32 so as to be capable of yielding and adjustment to accommodate expansions of the kiln.

A suitable fuel supply pipe 33 extends centrally through the firing hood 31 and into the kiln 10 as indicated and whereby fuel is supplied to the kiln in the usual way.

A tubular discharge member 34 having a suitable removable lining as indicated is provided for the kiln and extends centrally through the wind box into the firing hood and discharges into a passageway 35 from which it is removed and treated in the usual way.

By these means air under pressure may be supplied to the chamber 11 while rotating in a simple and efficient manner and without the employment of circumferential projections on a wind box surrounding the same as were employed in the constructions of my said prior patents, and whereby the vertical and lateral dimensions of the kiln are materially decreased without impairing its capacity and complicated and expensive connections with the kiln avoided. Owing to the fact that tubular discharge 34 extends entirely through the wind box, the clinker from the kiln is prevented from falling upon and working into the bearing surfaces between the wind box and kiln and the consequent wear thereon thus prevented. The specific construction disclosed is a simple and effective one for the purpose.

In the modification illustrated in Figs. 7 and 8

the wind box 14 is swingingly supported in a gallows frame 36 upon swinging hangers or links 37 and a firing hood 38 is rigidly connected to said wind box. The firing hood 38 is also provided with a discharge spout 39 for conducting the discharged clinker to the passageway 35. Cables 40 are also connected with the wind box and with weights 41 whereby the wind box is yieldingly held seated against the end of the chamber 11. Otherwise the construction and operation is the same as above described.

While I have illustrated and described the preferred forms of construction for carrying my invention into effect, these are capable of variation and modification without departing from the spirit of the invention. I, therefore, do not wish to be limited to the precise details disclosed but desire to avail myself of such variations and modifications as fall within the scope of the appended claim.

I claim:

A kiln comprising a rotary chamber; a non-rotating wind box seating against the end of said chamber, said chamber and wind box being provided with cooperating elements permitting the passage of air from the box into the chamber, there being a central opening extending through said wind box; means for supplying air under pressure to said wind box; and a tubular discharge for said chamber extending centrally from the adjacent end of said chamber and passing freely through the opening in said wind box.

HENRY VANDERWERP.
